UNITED STATES PATENT OFFICE.

CHARLES E. PIPP, OF PLAINWELL, MICHIGAN, ASSIGNOR TO ANGLE STEEL STOOL COMPANY, INC., OF PLAINWELL, MICHIGAN.

CHAIR AND CLAMP FOR PARTS THEREOF.

Application filed August 9, 1926. Serial No. 128,195.

The main objects of this invention are:

First, to provide an improved chair with an adjustable back in which the parts are very simple and economical to produce and at 5 the same time are strong and rigid, the chair being especially designed for factory and shop use.

Second, to provide an improved clamp for joining angle iron and flat parts such as the 10 angle iron legs and back supporting parts of a chair of the class described.

Objects pertaining to details of my invention will definitely appear from the description to follow. The invention is defined in 15 the claims.

A structure embodying the features of my invention is illustrated in the accompanying drawing forming a part of this application, in which:

20 Fig. 1 is a front perspective view of a chair embodying the features of my invention.

Fig. 2 is a fragmentary rear perspective view.

25 Fig. 3 is a horizontal section on a line corresponding to line 3—3 of Fig. 2.

Referring to the drawing, my improved chair in the embodiment illustrated comprises a seat 1 supported by angle iron legs 2 disposed to face inwardly. The seat has a 30 metal rim 3 to which the legs are secured by the rivets 4. The legs are provided with braces 5 and 6.

The back 7 is supported by the upright bars 8 which are flat and are disposed against 35 the rear sides of the rear legs as shown in Figs. 2 and 3. The U-shaped clamps 9 are arranged to embrace the back uprights and legs with their bights 10 engaging the uprights. The cross bars 12 of the clamps are 40 provided with inwardly-projecting lugs 13, the lugs being arranged to engage the inner sides of the rear arms of the angle iron leg members, as shown in Fig. 3. The bolts 14 securely clamp the parts together.

45 By this means the flat bars 8 are very effectively secured to the legs and in a manner that permits the vertical adjustment of the back as may be desired.

I have illustrated my improvements in an embodiment which I have found very practical. I have not attempted to show various adaptations of my improvements which I contemplate as I believe the disclosure made will enable those skilled in the art to embody or adapt the same as may be desired. 50 55

Having thus described my invention, what I claim as new and desire to secure by Letters Patent is:

1. The combination with an angle iron member, of a flat frame member disposed 60 against one arm thereof with one edge in the plane of the outer side of the other arm, a U-shaped clamp disposed with its bight embracing and closely fitting said flat member, one arm of the clamp being disposed 65 against the side of the angle iron member with which the edge of said flat member is aligned, the arms of said clamp having threaded end portions, a cross bar having openings to receive the ends of said clamp 70 and an inwardly projecting lug engaging the inner side of the arm of said angle iron member against which said flat member is disposed and in opposed relation thereto, and clamping nuts threaded upon the ends of the 75 arms of said clamp.

2. The combination with an angle iron member, of a flat frame member disposed against one arm thereof with one edge in the plane of the outer side of the other arm, a 80 U-shaped clamp disposed with its bight embracing said flat member, the arms of said clamp having threaded end portions, a cross bar having openings to receive the ends of said clamp and an inwardly projecting lug 85 engaging the inner side of the arm of said angle iron member against which said flat member is disposed and in opposed relation thereto, and clamping nuts threaded upon the ends of the arms of said clamp. 90

In witness whereof I have hereunto set my hand.

CHARLES E. PIPP.
